UNITED STATES PATENT OFFICE.

AUGUST W. OFELDT, OF JERSEY CITY, NEW JERSEY.

WATER-TUBE BOILER.

1,104,379.

Specification of Letters Patent.

Patented July 21, 1914.

Application filed October 30, 1913. Serial No. 798,362.

To all whom it may concern:

Be it known that I, AUGUST W. OFELDT, a citizen of the United States of America, and a resident of Jersey City, county of Hudson, State of New Jersey, have invented a certain new and useful Water-Tube Boiler, of which the following is a specification.

My invention relates to improvements in water tube boilers, and particularly to means for insuring cleaning of the generating tubes during blowing off of the boiler.

My invention consists in means for forcing the steam to pass through the generating tubes during the blowing off of the boiler, which means, however, does not interfere with normal water circulation during normal operation of the boiler.

The object of my invention is to insure cleaning of the generating tubes of steam boilers, particularly coiled generating tubes, during blowing off of the boiler.

I will now proceed to describe my invention with reference to the accompanying drawings and will then point out the novel features in claims.

In said drawings: Figure 1 shows a central vertical section of a boiler embodying my invention; Fig. 2 a horizontal section of the boiler; and Fig. 3 a detail vertical section of one of the float valves.

In the drawings 1 designates the outer shell of the boiler and 2 an inner shell, the space within this inner shell constituting the fuel and combustion space. I customarily close the annular space between the inner and outer shells of the boiler by rings 3 and 4 welded to the inner and outer shells.

5 designates the fire door opening, 6 the fire door and 7 the frame of the fire door opening, which frame is also, customarily, welded to the outer and inner shells 1 and 2.

8, 8 designate generating tubes which, in the construction shown, are pipe coils, connected at the ends to the annular space between the outer and inner shells 1 and 2. In practice, the ends of these pipe coils 8 are welded into suitable openings in the inner shell 2.

9 designates the steam discharge connection, and 10 the blow off connection, the latter being provided, as is customary, with a valve 11.

The space between the outer and inner shells 1 and 2 constitutes the water and

steam space of the boiler, the water level being carried, usually, to a point near the upper ends of the pipe coils 8. It will readily be seen that if (except for the means hereinafter described) the water in the boiler were to be drawn off by opening the blow off valve 11, steam would not be forced through the coils 8 to any material extent, and therefore, though water in those coils might be drawn off, sediment and scale deposited within such coils would not necessarily be carried away. To insure the carrying off of sediment and scale deposited within the pipe coils 8, I divide the annular steam and water space between the outer and inner shells 1 and 2, by a ring 12, preferably welded to the inner and outer shells 2 and 1, and provided with valve openings 13 adapted to be closed by valve plugs 14 provided with floats 15. The ring 12 is located between the upper and lower ends of the pipe coils 8. When the boiler is filled with water to a point above the floats 15 these floats will hold the valves 14 open, permitting normal water circulation. But when the boiler is blown off by opening the valve 11, while the boiler is under steam pressure, as the water level falls the valves 14 will close, forcing the steam liberated from the water above these valves to pass through the coils 8 into the space below the ring 12, thereby thoroughly scouring the interior of these coils 8 and thereby freeing these coils from deposited sediment and scale.

Heretofore much difficulty has been experienced in the cleaning of the generating tubes of water tube boilers, particularly when such tubes are of curved form, and still more particularly when such tubes are coiled. The present invention overcomes this difficulty, the mere opening of the blow off valve 11, while the boiler is under steam pressure, causing the steam to pass through the coils and thereby to thoroughly scour the same.

The boiler herein illustrated and described is particularly intended for use in house heating systems, and is not intended to be operated under great pressure. However, I do not restrict my invention to low pressure boilers, as the invention is equally applicable to boilers intended to operate under high pressure; and my invention is

also independent of the particular character of fuel to be used in the boiler, *i. e.*, whether the fuel to be used be solid, liquid, or gas.

What I claim is:

1. In a boiler, the combination with a structure comprising a steam and water space, having a valved blow off connection, a heating space, and generating tubes in that heating space each connected at both ends 10 to said steam and water space, of a ported partition located in such steam and water space between the ends of such generating tubes, and dividing such steam and water space into separate chambers, and valve 15 means controlling flow through the port or ports of such partition and normally open but adapted to close such port or ports when the blow off connection is opened.

2. In a boiler, the combination with a structure comprising a steam and water space, having a valved blow off connection, a heating space, and generating tubes in that heating space each having its ends connected to said steam and water space at different levels, of a ported partition located 25 in such steam and water space between the ends of such generating tubes, and dividing such steam and water space into separate chambers, and valve means controlling flow 30 through the port or ports of such partition and normally open but adapted to close such port or ports when the blow off connection is opened.

3. In a boiler, the combination with a structure comprising a vertical annular steam and water space having a valved blow off connection, a heating pipe within such annular steam and water space, and generating tubes in that heating space each having 35 its ends connected to said steam and water space at different levels, of a ported partition located in such steam and water space between the ends of such generating tubes, and dividing such steam and water space 40 into separate chambers, and valve means

controlling flow through the port or ports of such partition and normally open but adapted to close such port or ports when the blow off connection is opened.

4. In a boiler, the combination with a structure comprising a steam and water space, having a valved blow off connection, a heating space, and generating tubes in that heating space each connected at both ends to said steam and water space, of a ported partition located in such steam and water space between the ends of such generating tubes, and dividing such steam and water space into separate chambers, and one or more float-operated valves controlling flow through 55 the port or ports of such partition and normally open but adapted to close such port or ports when the blow off connection is opened.

5. In a boiler, the combination with a structure comprising a steam and water space, having a valved blow off connection, a heating space, and generating tubes in that heating space each connected at both ends to said steam and water space, of a ported partition located in such steam and water space between the ends of such generating tubes, and dividing such steam and water space into separate chambers, and one or more float-valves controlling flow through 75 the port or ports of such partition and normally open but adapted to close such port or ports when the blow off connection is opened, each such float valve comprising a valve plug above the partition, a stem passing 80 through the corresponding port of that partition, and a float beneath such partition and connected to such stem.

In testimony whereof I have signed this specification in the presence of two subscribers.

AUGUST W. OFELDT.
